(71) Applicant: **Waymo LLC**, Mountain View, CA (US)

(72) Inventors: **Peter Crandall**, San Jose, CA (US); **Nirmal Patel**, Sunnyvale, CA (US)

(73) Assignee: **Waymo LLC**, Mountain View, CA (US)

(**) Term: **15 Years**

(21) Appl. No.: **29/983,273**

(22) Filed: **Jan. 9, 2025**

Related U.S. Application Data

(63) Continuation of application No. 29/803,214, filed on Aug. 11, 2021, now Pat. No. Des. 1,063,982, which is a continuation of application No. 29/623,844, filed on Oct. 27, 2017, now abandoned.

(57) **CLAIM**

The ornamental design for a display screen or portion thereof with icon for a vehicle as shown and described.

DESCRIPTION

FIG. 1 is a front view of the claimed design for a display screen or portion thereof with icon for a vehicle; and, FIG. 2 is a front view of an alternative embodiment of the claimed design for a display screen or portion thereof with icon for a vehicle. The peripheral uneven-length broken lines showing a display screen or portion thereof illustrate boundaries of the claimed design and form no part thereof. The even-length broken lines showing elements of the graphical user interface illustrate portions of the article and form no part of the claimed design.

1 Claim, 2 Drawing Sheets
